REFRIGERATOR CAR

George A. Steuber, Penfield, N. Y., assignor to
Despatch Shops, Inc., a corporation of New
York

Application April 10, 1939, Serial No. 267,134

5 Claims. (Cl. 105—376)

According to my invention the refrigerator car ice chamber bulkhead is so attached to the car that it may be moved out of position for inspection or repair of the ice chamber, also to leave the car free from end to end to enable the shipper to load the car to full capacity with flour and certain metals and other lading, while not requiring refrigeration, does require protection from dampness and the like; and it has been found that such laden is more completely protected in the tightly built and insulated refrigerator cars than in other types of cars.

One of the objects of my invention is to provide a bulkhead for refrigerator cars adjustable as a unit by means of a hoist and means to hold it safely in an adjusted position.

Another object of my invention is to house the bulkhead operating hoist above the car ceiling, thus leaving the inside of the car free from obstruction, thereby protecting the hoist from moisture and dirt which may collect in the car.

Another object of housing the hoist above the car ceiling is that I am thus enabled to leave the car ceiling and inside wall sheathing flush throughout the car, which not alone adds to the inside appearance of the car but leaves the walls and ceiling free from obstructions which may interfere with loading or damage goods packed in the car.

Another object of my invention is to provide a seat for the bottom edge portion of the bulkhead, flush with the floor of the car, which positively prevents any movement of the lower edge of the bulkhead except the raising and lowering movements of the bulkhead.

Another object of my invention is to provide an automatic lock to hold the bulkhead in its full elevated position against accidental movement.

Another object of my invention is to provide a refrigerator car with a unit bulkhead with means for raising and lowering it as a unit in a vertical and horizontal direction without traversing the space in the car except near the ceiling of the car.

Another object of my invention is to provide a door in the ceiling of the car whereby the bulkhead hoist can be reached, inspected, repaired and oiled when necessary.

Another object of my invention is to provide means connecting the ceiling door with the automatic safety bulkhead lock whereby when the ceiling door is in open position the safety lock is moved to inoperative position whereupon the bulkhead may be moved by the operation of the hoist.

Another object of my invention is to have the

side walls of the ice chamber flush with the side walls of the car.

Another object of my invention is to provide the ceiling door with a receptacle for the chain of the hoist; and with these and other objects in view, my invention consists of the parts and combination of parts herein described.

In the drawings:

Figure 1 is a detail perspective interior view of the ice bunker end of a refrigerator car embodying my invention.

Figure 2 is a vertical longitudinal sectional view of the same.

Figure 3 is a detail view, parts being in section showing the bulkhead, its track, and the automatic safety lock in inoperative position.

Figure 4 is a detail view somewhat similar to Figure 3 showing the bulkhead in elevated stored position with the safety lock in operative position.

Figure 4a is a detail view immediately to the right of Figure 4, showing the hoist, the ceiling door and the operative connection between the ceiling door and safety lock.

The reference numeral 1 designates a refrigerator car of any desired construction having a lattice floor 2 and an ice bunker 3 having a suitable drain 4.

The ice bunker is provided with a perforated lining 5 spaced from the imperforate end and side walls 6, 7, thus leaving a space between the lining and wall for air circulation. Suitable ice trays 8 are provided for the bunker which may be supported the desired distance above the bottom of the bunker, according to the amount of ice to be placed in the bunker. The perforated lining sheets on the opposite sides of the bunker are positioned so that they will be flush with the wall sheathing 9.

At the front of the bunker 3 vertically disposed tracks 10 are secured diametrically to each other on the side walls of the car, and at the bottom of these tracks 10 countersink in the floor of the car a bulk head seat 11 extending transversely of the car.

A track 12 is secured to each side wall of the car near the car ceiling 13, said tracks having a stop 14 at one end while the other end of these tracks are gradually increased in width at the other end as at 15, the lower wall 16 of the track being curved downwardly and gradually merging with the outer wall of the vertical track 10, as clearly shown in the drawings. The lower wall of the track 12 is provided with bolt openings 17 and 18 to be hereinafter referred to.

A bulk head 19, which may be of any desired

construction, is designed to slide in the trackways 10 and 12, and is shown in Figure 2 in its lowered or closed position, and in Figure 4 in its elevated position, said bulkhead being provided with guiding rollers 20. In its lowered or closed position the bottom edge portion of the bulkhead is seated in the seat 11 which positively prevents any movement of the base of the bulkhead except, of course, its vertical movement.

10 The bulkhead is provided on its inner face near the bottom with an eye 21 which is secured to the bulkhead by means of the plate 22 held in position by means of the rivets 23.

15 A cable 24 is secured at one end to the eye 21, thence passes upwardly back of the bulkhead through a ferrule 24a in the ceiling 13 of the car, thence over a pulley 25 to a chain hoist 26 to which its other end is operatively connected, the chain hoist being operated by means of the chain 27 which hangs down, as shown in dotted lines in Figure 4a, into the car when the bulkhead is to be operated.

20 A safety catch 28 is pivotally mounted as at 29 to a plate 30 secured to the ceiling 13 of the car and within and at the top of the bunker, as clearly shown in Figure 2, said safety catch having a bulkhead stop 31 at its free end. This safety catch is connected at 32 to a cable 33, which cable extends over a pulley 34, thence along the underface of the ceiling of the car through a conduit 35, thence upward through a ferrule 36 through the car ceiling 13 over a pulley 37, the free end of the cable being attached by means of the staple 38 to a ceiling door 39, as clearly shown in Figure 4a. With the parts in position, shown in Figure 2, the ceiling door 39 is normally closed, leaving the safety hook in the position shown in Figure 2. However, when the ceiling door 39 is lowered to the position shown in dotted lines, Figure 4a, the safety hook is moved rearwardly in the direction of the arrows, shown in Figure 3, because of the pulling of the ceiling door 39 on the cable 33.

25 When the ceiling door 39 is in the lowered position shown in Figures 1 and 4a the chain hoist is operated by means of the chain 27, which operation pulls on the cable 24, which, in turn, pulls the bulkhead 19 upwardly in the vertical tracks 10, and in continued movement the lower rollers 20 guide the upper end of the bulkhead on to the tracks 12 until the bulkhead assumes the horizontal position shown in Figure 4. When the bulkhead is in this position the ceiling door 39 is closed thus permitting the cable 33 to slack whereupon the counterweight safety catch 28 assumes the position shown in Figure 4 by gravity, the safety catch straddling the bottom of bulkhead 41 and the stop 31 functions to move into engagement with the lower end portion of the bulkhead 31a in the event that the bulkhead, for any reason, attempts to slide rearwardly on the tracks 12, in which case the stop 31 would engage the projection 31a of the bulkhead and thus prevent further movement of the bulkhead toward closing position. I regard this safety catch as an important feature because in the past bulkheads have been known to close accidentally as a result of which operators have been injured.

30 The bulkhead is raised and lowered as a unit, and by means of the chain hoist it may be raised to any height that may be desired for purposes of inspection. As a further safeguard against the bulkhead being accidentally closed I provide it with stop bolts 40 which, when the bulkhead is in the elevated position shown in Fig-

ure 4, engage suitable bolt openings 47 and 48 of the track 12, and when in lowered position these stop bolts engage suitable bolt openings in the side walls of the car.

35 As will be seen from Figure 3, the lower portion of the bulkhead is more or less wedge shape as at 41 thereby providing a snug fit with the track seat 11 in the floor of the car.

The ceiling door 39 is provided with a back or other receptacle 42 in which the main portion 10 of the hoist chain 27 is housed when the ceiling door 39 is in a closed position, shown in Figure 4a whereby the chain is protected above the ceiling of the car from moisture, et cetera, when the chain hoist is not in operation.

40 A substantial metal brace 43 is positioned at 15 the top of the bunker, and extends the full width of the car, it being reinforced by a plurality of pressed steel gussets 30.

45 As will be seen, the chain hoist is positioned between the ceiling and the roof of the car and is thus protected from moisture and dirt which might collect in the body and permits flushing the side wall and ceiling of the car and adds to the interior appearance of the car by being so concealed. It is still accessible for repairs and such work as oiling, if necessary.

50 Refrigerator cars by reason of their construction to resist the elements are preferred by shippers of flour, et cetera, for this reason, because there is no danger of the commodity being damaged by dampness en route. In such shipments the bulkhead is raised to the overhead position as shown in Figure 4 and is held safely in such position by means of the stop bolts 40 independent 30 of the cable 24 and safeguarded against possible movement by safety catch 28, thus leaving the inside of the car free of obstruction from end to end, and as the perforated side sheets of the ice bunker are flush with the inner side 35 sheathing of the car loading is facilitated to the full capacity of the car. Again, when used for such shipment the ice tray 8 is placed in the bottom of the ice bunker so that the bottom of the 40 bunker will be flush with the floor of the car.

55 It will be seen from the above that there are a minimum of mechanical gadgets in my construction to be operated by hand, or left to the discretion of an operator, thus giving a maximum insurance against the operator being injured by accidental movement of parts.

60 What I claim is:

1. In a refrigerator car, an ice bunker, tracks extending vertically in front of the bunker, and horizontally near the ceiling of the car, a unit bulkhead movable on said tracks, a lifting hoist mounted between the car ceiling and roof, a cable connecting said hoist and bulkhead to move the bulkhead on said tracks, and means to hold the bulkhead on the horizontal tracks against 65 accidental movement.

2. In a refrigerator car, an ice bunker, a unit bulkhead hoisting mechanism mounted between the car ceiling and roof, means connecting the bulkhead and hoisting mechanism, a door in the car ceiling sealing the hoisting mechanism from the body of the car proper, and through which the hoisting mechanism may be operated from the body of the car.

3. In a refrigerator car, an ice bunker, a unit bulkhead hoisting mechanism mounted between the car ceiling and roof, means connecting the bulkhead and hoisting mechanism, a door in the car ceiling sealing the hoisting mechanism from the body of the car proper, through which the 75

hoisting mechanism may be operated from the body of the car, a gravity safety catch to hold the bulkhead in open position against accidental movement, and connecting said catch and door whereby when the said door is in closed position the said catch is free to move to its operative position.

4. In a refrigerator car, an ice bunker, vertical tracks in front of said bunker, and extending horizontally on the car side walls near the ceiling of the car, a unit bulkhead movable on said tracks, a hoist positioned between the car ceiling and roof, a cable connecting the said hoist and bulkhead, a door in the car ceiling through which the hoist is operated, a safety catch, a cable connecting said catch and door, whereby when the door is in closed position the catch is free to move into operative position to hold the bulk-

head in position on the horizontal track against accidental movement.

5. In a refrigerator car, an ice bunker, vertical tracks in front of said bunker, and extending horizontally on the car side walls near the ceiling of the car, a unit bulkhead movable on said tracks, a hoist positioned between the car ceiling and roof, a cable connecting the said hoist and bulkhead, a door in the car ceiling through which the hoist is operated, a safety catch, a cable connecting said catch and door, whereby when the door is in closed position the catch is free to move into operative position to hold the bulkhead in position on the horizontal track against accidental movement.
